AIR CLEANER FOR FLAT KNITTING MACHINES

Louis Imbriani, Corona, N. Y., assignor to Frances Speier, doing business as Knitcraft Mills, Corona, N. Y.

Application September 13, 1948, Serial No. 49,006

26 Claims. (Cl. 66—168)

1

This invention relates to air cleaners for flat knitting machines. One of the great difficulties with flat knitting machines is the accumulation of lint on the beds, needles and jacks. It has heretofore been necessary to stop the machines at intervals and clean off the lint to prevent defects in the fabric, breakage of parts of the machines, etc. I have invented an air-cleaning mechanism suitable for flat knitting machines which is entirely automatic and will not disturb the movements of the parts in any way. It is characteristic of my air cleaner that there are one or more air nozzles on the moving cam carriage located at points just ahead of the knitting cams to blow away the lint automatically at intervals controlled by the ordinary operations of the machine.

The invention will be shown and described embodied in a flat purl Links and Links knitting machine. Such a machine has a single set of double-ended needles moving back and forth between two parallel beds lying in the same plane, the needles being actuated by jacks which are controlled by cams in the usual carriage moving lengthwise back and forth over the beds. It should be understood, however, that in most of its aspects the invention is applicable to any flat knitting machine having independent needles.

In the drawings.

Figure 1 is a view in elevation from the left end of the pertinent parts of a flat purl knitting machine in which my air cleaner has been incorporated;

Figure 2 is a plan view of so much of the left end and the carriage of the machine of Fig. 1 as is necessary to show the air connections and controls;

Figure 3 is a partial view in elevation from the front of the machine of Figs. 1 and 2 showing the carriage and the air control trip lever when the valve is closed;

Figure 4 is a view in elevation of the trip lever and associated yarn slide with the valve open;

Figure 5 is a detail plan view showing the air line broken when the carriage has been stopped by a broken jack;

Figure 6 is a view in elevation corresponding to Fig. 5;

Figure 7 is an inverted plan view of the cams of the front bed of the machine of Figs. 1 to 6 showing the position of one of the air nozzles, the nozzles being shown laid down, for clarity, but actually lying in a vertical plane as shown in Figs. 1 and 2;

2

Figure 8 is a view in inverted side elevation of the Winkel cam of Fig. 7;

Figure 9 is a plan view of so much of the left end and the carriage of a modified form of machine containing four nozzles as is necessary to show the air connection and controls of my invention; the air hose being shown disconnected from the carriage;

Figure 10 is a plan view similar to Fig. 9 of the modification showing the air hose connected to the carriage and the latter beginning to move to the right; while

Figure 11 is an inverted plan view of the main knitting cam blocks of the two beds of the modification of Figs. 9 and 10.

This application is a continuation-in-part of my abandoned application filed December 24, 1947, Serial No. 793,635, for "Air cleaner for flat knitting machines."

I shall first describe the embodiment of Figs. 1-8. As already mentioned, a straight or flat knitting machine adapted to make purl stitches is sometimes known as a Links and Links machine. It is a flat bed machine containing double-ended needles. I have shown latch needles, but bearded needles can also be used. Such a machine has two flat needle and jack beds 1, 2 lying parallel to each other with a space therebetween for the fabric known as the throat 3. The slots 4 in the beds are opposite each other so that the needles 5 may move from one bed to the other at different times, thereby making plain Jersey fabric or purl stitches, as may be required. These machines frequently have jacquard mechanism incorporated in them to produce purl stitch designing, but my invention is not concerned with the presence or absence of jacquard mechanism. For each needle 5 there is a jack 6 in each of the two beds, and the cam 7 for operating the needles operates on butts on the jacks 6. Each jack has, as usual, a hump 7 and clutch 8, the latter being adapted to engage and hold a hook of the needle (see Fig. 7).

To operate the jacks and needles there is the usual carriage 9 sliding along on top of the two needle beds on slide bars 10. This cam carriage 9 is driven from the main drive chain 11 of the machine through a drive arm 12 at the back of the machine (see Fig. 1). This drive arm slides on a horizontal bar and is connected to the main drive chain 11 by a yoke 14 rigidly connected to the drive arm. This yoke has an open vertical slot 15 beside the main drive chain 11. In the open slot lies a slide 16 pivotally attached to the side of one of the links of the chain. The slide

transmits the reciprocatory motion to the drive arm 12 as the chain moves forward continuously.

The drive arm 12 is connected to the carriage 9 by means of the usual pressure release mechanism 17 which engages the free upper end 18 of the drive arm. The release mechanism is rigidly associated with the carriage. The purpose of such pressure release means is to save the machine from damage when the carriage meets an obstruction, e. g., a misplaced jack or the like. Such pressure release means is adapted to disconnect the free upper end 18 of the drive arm from the pressure release means when such an obstruction is met, so that the carriage can remain stationary while the driving means continue until stopped by the following means. The free upper end 18 of the drive arm 12 is pivotally mounted in the drive arm and when the carriage is disconnected, as shown in Fig. 6, the free upper end 18 is above the release mechanism 17. The latter has been lowered into a position of contact with a rod 19 lying lengthwise of the machine. This contact closes an electrical circuit that shuts off the power. These parts are old and need no detailed description.

The carriage contains the usual cams for operating the jacks in both beds. Disregarding any parts intended for jacquard purposes, the cams for each bed divide themselves into groups or cam blocks—the purl cam block for transferring needles from one bed to the other, and the main knitting block (see Fig. 7). Each main knitting cam block contains, in addition to various guard cams, the knitting cams for the production of plain or Jersey stitches. This main cam block is the longer one in Fig. 7 and is separated from the shorter or purl block by a space occupied by the usual gib 20. The purl block is nearer the throat 3. The purl cam block, operating in conjunction with the usual purl stitch cam 21 in the main knitting cam block, cooperates, as usual, with the corresponding elements in the other bed to cause transfer of needles from one bed to the other when purl stitches are desired. The main cam in the purl cam block is occupied by the Links and Links or purl bridge cam 22. The outer ends or points 23 of this bridge cam serve to hold down the needles passing under it as the flat portions 24 of the needles come under the purl bridge cam. The two small side cams 25 near the throat 3 are known as "latch-opener" cams, and the central cam 26 in this block furthest from the throat is known as the "Winkel" cam. It is shown in inverted side elevation in Fig. 8. This cam is also known as a "bridge." It will be observed that the lower edge of the Winkel cam which faces downwardly in the machine is hollowed out in a corner or notch 27. This notch is positioned about opposite the left part of the purl stitch cam 21 in the main cam block. As shown in Fig. 7, the purl bridge cam 22 is hollowed out above the Winkel cam 26 in correspondence with the path that would be taken by a jack butt passing over the purl stitch cam 21. It will be noted that this cut-out corresponds to a cut-out 28 in a cover or main knitting bridge cam 29 in the main cam block. The cut-out 28 serves to guide the jack butts that are passing over the purl stitch cam 21. The cover or bridge cam 29 also encloses the path for jack butts passing the knitting cam 30 of the main knitting block. On either side of the main bridge cam 29 and also forming part of the cam surfaces for the jack butts are two cast-off cams 31. These cams extend outward from the throat of the machine a considerable distance beyond the

main bridge cam 29 (see Fig. 7). Beside each of these cams are a guard cam 32 and a retracting guard cam 33. Opposite these cams 31, 32 and 33 and beside the knitting cam 30 are other side 5 cams 34, the path of the jacks therefore being enclosed from the time they enter between the retracting guard cam 33 and the lower side cam 34 at one end of the block until they emerge between the companion cams at the other end.

10 It is noted that when a jack butt is riding along the lower or outer edge of a guard cam 32, the forward end of its needle is about even with the edge of the purl cam block close to the throat. When the jack cam butt is riding along that portion 15 of the surface of the main knitting cam 30 indicated by the reference character 66 in Fig. 7, the needle is in its cleared position, and it is in this position that the needle takes yarn. The location of the active yarn carrier lengthwise of 20 the carriage is opposite the point marked 66. The yarn is not fed to a needle until after it has passed the purl stitch cam 21. Therefore the yarn carrier at the position 66 is following the purl stitch cam 21 in the direction of movement 25 of the carriage which is the one used to feed yarn. The knitting cam is the one which we have heretofore identified as cast-off cam 31. It is not necessary to describe the function of the purl stitch cam 21 and the other cams in the purl 30 stitch cam block further than above explained, except to say that when a jack is pushed out by the purl stitch cam 21, the forward hook of the needle is caught by the clutch 8 of the jack 6 in the opposite bed, and that by means of the notch 35 27 in the Winkel cam 26 the jack which pushed the needle out to this position is able to release the needle as the jack in the other bed is guided down off its own purl stitch cam, taking the needle with it.

40 The yarn carriers which I have identified in my drawings by the reference character 35 are mounted on slide bars 36 (Fig. 1). The yarns 37 may come from any convenient rack or other holder to the left end of the machine passing 45 through a guide bar 40 direct to the yarn carrier 35. The changing of yarn either at the ends of the machine or at the midpoint is occasioned by the usual stops (not shown). The stops at the left end of the machine control two of the usual 50 yarn slides 38, 39. For purposes of illustration, let us assume that the rear or upper slide 39 as it appears in Fig. 2 is for the regular body yarn and that the front or lower side 38 in this figure controls what may be termed a "separating" 55 thread. This separating thread is one which may be used between garments and can be drawn out later to separate the garments. I have shown these two yarn slides 38 and 39 so interconnected that only one of their yarns can feed at a time. 60 To understand this arrangement it should be noted that when one of these yarn slides is in its left-most position in the machine, its yarn will not be fed. When one of these yarn slides is moved to the right to the position of yarn slide 65 39 in Fig. 2, the yarn controlled by that slide will begin feeding to the needles.

These two slides are carried on the upper frame of the carriage 9 (see Figs. 1 and 3). As shown in the plan view of Fig. 2, each slide 38, 39 has a 70 short group of rack teeth 41 on its edge facing toward the other slide. Located between and engaging both sets of rack teeth is a pinion 42 fixed on the carriage but rotatable. Thus, if one of the slides is moved from inoperative to operative position, the companion slide will move in

the opposite direction to inoperative position. Unless engaged by some stop element these yarn slides will move back and forth with the carriage without changing their relationship.

A stop arm 43 is located at one end of the machine which can be swung into the path of the yarn slides as the carriage comes to the end of its movement. This is a customary means of changing the position of the yarn slides when it is desired to change the yarn feeding. I have shown a stop at only the left end of the machine, but it will be obvious that stop arms at both ends could be used in carrying out my invention, if desired. The double stop arm 43 is pivoted below the yarn slides and is moved from one position to another by a link 44 connected to one of the usual control rods running lengthwise of the machine to the usual chain controls at the right end of the machine. In Fig. 2 one arm of the double yarn stop arm 43 is in line with the slide 39, and the carriage being in its left-most position, this slide has been moved to the right into its yarn-feeding position. Therefore the yarn slide 38 has been moved by the rack and pinion 41, 42 to the left so that its yarn will not be feeding. It will be obvious that as the carriage moves toward the right of the machine, the yarn controlled by slide 39 will be fed to the needles and the yarn will also be fed to the needles as the carriage returns to the left end of the machine. In the particular embodiment of my invention which I am describing, no stop arm will be in line with either slide 38 or slide 39 at the right end of the machine. It will be obvious that if the stop arm 43 were swung until one of its arms is in the path of the slide 38, then when the carriage 9 next comes to the left end of the machine the cam slide 38 would be moved to a position where its yarn would begin to feed and that yarn would feed for one complete reciprocation. If, on return to the left end of the machine from that reciprocation, the stop arm 43 were in position shown in Fig. 2, the yarn slide 38 would then be moved out of its operative position and slide 39 moved into feeding position so that the yarn associated with slide 38 would have fed for one course in each direction of movement of the carriage. With a stop at the right end to move the slide 38, there would be only one or an odd number of courses of the separating thread.

As indicated above, lint collects quite rapidly on the needle and needle beds of a purl knitting machine, and eventually that lint will cause trouble either by making defects in the knitting or by clogging the machine so that jack butts break. For this reason it has heretofore been necessary to stop the knitting and clean the machine periodically. I have invented an air cleaner which is so arranged that it does not upset the knitting operation and will clean the machine automatically at regular intervals. In the first place, my air cleaner involves the provision of a compressed air supply on the reciprocating carriage of the machine, and I will first describe how that air supply on the carriage is obtained.

From any desired stationary compressed air supply at the rear of the machine I connect a rubber hose or other flexible pipe 45 (see Fig. 1). This hose is connected by means of a fixed piece of pipe 46 on the drive arm 12. At the upper part of the drive arm 12 this pipe 46 is connected swivelly to a horizontal length of pipe 47 which carries the connection forward to a position where it terminates swivelly in a valve socket 48 facing toward the front of the machine. This

socket 48 is mounted on the free upper end 18 of the drive arm 12 and preferably is above the center of the pressure release mechanism for the carriage drive. The swivelling of the pipe 47 is at such an angle and length that when the regular pressure release mechanism frees the carriage, as shown in Fig. 6, the pipe 47 does not interfere with the free upper end 18 and the pipe and socket 48 swinging upwardly. This socket has a valve in it similar to that of an automobile tire valve or the like, but much larger, and provides one side of a breaking point for the air supply corresponding to the breaking point between the drive arm and the carriage. The pipe means to which it connects is carried by the carriage. There is a short length of pipe 49 appreciably smaller in diameter than the inside of the socket 48 which is adapted to engage in the valve socket and provide air-tight connection when mounted in the manner that I shall now describe. As can be seen, this short pipe 49 is held horizontally facing toward the rear of the machine by an elbow piece 50 extending vertically downward through a horizontal plate 51. This elbow piece 50 is held loosely in an open slot 52 in one end of the horizontal plate. The elbow piece 50 not only extends through the horizontal plate 51 but extends horizontally under the plate to the mid-point where it is pivotally connected by means of two nuts 53 to a length of pipe 54 projecting upwardly through the middle of the plate. This upwardly-extending support pipe 54 in turn is connected by elbows and pipes 55 horizontally across the top of the carriage, then downwardly along the far or front side of the carriage and horizontally to the left end of the carriage by means of pipe 56 where it terminates in a nozzle 57 located above the front bedplate 2 in a particular location and manner which will be described later.

Taken off the piping 56 by a T is an extension 58 which leads back to the rear of the carriage, then along the carriage toward the right to a position near the right-hand end where it terminates in a nozzle 59 over the rear bed 4.

There is a coiled spring 60 on the support pipe 54 which tends to turn the horizontal plate in a counterclockwise direction as the parts are viewed in plan (see Fig. 5). In addition there is a tension spring 61 from the rear or free end of the horizontal plate 51 connected to any suitable fixed part of the carriage. This pulls the open slot 52 of the horizontal plate 51 toward the valve socket 48 on the upper free end 18 of the drive arm 12. When the short pipe 49 is placed in the valve socket 48 these two springs tend to keep the connection air-tight. When the connection is once broken by the carriage becoming disconnected, the short pipe will swing out of the socket 48 and assume the position shown in Figs. 5 and 6 of the drawings.

The compressed air preferably does not come out of nozzles 57 and 59 continuously because of the presence of a valve 62, spring-pressed closed, located in a vertical portion of the pipe 56 on the front of the carriage preceding the nozzles. This valve is adapted to be opened by a trip lever 63 pivotally mounted on a fixed part of the carriage. The pressure of the air tends to close the valve. The upper end of this trip lever extends upwardly alongside the front yarn slide 38 to a position slightly above the upper face of the yarn slide. Mounted on the upper face of this yarn slide 38 is a cam plate 64 extending laterally into the path of the upper end of the trip lever. This

cam plate is so located that if the yarn slide 38 is moved to the right to the position in which its yarn will be feeding to the needles, the cam plate will slide over a roller 65 on the upper end of the trip lever and pivot that lever, causing the valve 62 to open. The valve will remain open until the yarn slide is moved to the left to its inoperative position. By arranging the yarn slide stop arms in the desired sequence, the air supply can be fed to the nozzles at any desired regular intervals. I have found it a convenient interval to open the valve 62 for a complete reciprocation of the carriage every time a garment is completed and the separating thread controlled by yarn slide 39 is used. This gives a cleaning by compressed air once in each direction of movement, in the particular manner that I will now describe.

I have found that the position of the nozzles has to comply with certain specific conditions in order that these nozzles may operate properly and not interfere in any way with the machine or its operation. I locate a nozzle over one of the knitting beds and ahead of the knitting cams. I have found it advisable to so locate the nozzle over the bed that is approximately above the mid-point of the double-ended needles at the time they are passing under the nozzle. I locate a similar nozzle over the second bed in advance of the knitting cams in their direction of movement over that bed. In a flat purl knitting machine such as shown in the drawings in this application using latch needles, the front bed knits as the carriage moves from right to left and the rear bed knits from left to right so that the nozzles 59 in the rear bed is towards the right end of the carriage and the nozzle 57 in the front bed is toward the left end of the carriage.

In order not to disturb the jacks and needles by the air blast, I have found it necessary also to locate the air blast at a point where the needles and jacks are held against longitudinal movement. This is one of the reasons why I locate the nozzles 57, 59 in a position which longitudinally of the carriage is only a short distance ahead of the knitting cams (see Fig. 7). It will be noted that the nozzle at the left of the carriage in the front bed is about opposite the guard cam 32 and at this point the jacks and needles cannot move longitudinally. The end of the needle is not projecting into the throat 3 of the machine. (The hump 7 on the jack at this point is under the gib 20 and therefore cannot release the needle, so that the jack and needle are locked against separation.) As indicated above, the nozzle is about opposite the flat portion 24 at the mid-point of the needle at this time. By having it in this position and close to the bevelled point 23 of the purl bridge cam 22, I have found that the air coming from the nozzle will not cause the needle to tip up as it passes from under the nozzle because this flat portion 24 on the needle is held down by the point of the purl bridge cam 22. I have found that by locating a nozzle in this position the air currents are not very far from the yarn carrier. To avoid disturbing the yarn in any way, I have therefore found it preferable to tip the nozzle away from the knitting cams and the active yarn carrier, and in the direction in which the carriage is moving. I have found that by locating it in the manner just described, a good cleaning operation can be obtained with an adequate safety margin against the various risks to which I have referred.

The operation of my novel air cleaner will now be set forth.

Assuming that the machine has been knitting in a reciprocatory manner with the yarn slides 38, 39 in the position shown in Fig. 2, the last reciprocation with the slides so adjusted takes place by a movement to the right from the position shown in Fig. 2 and a return movement. While this is taking place, the double yarn carrier slide 10 stop arm 43 has been moved from the idle position where it is not opposite either of the two yarn carriers, to a position in which one of its arms is in line with the left end of the front yarn slide 38 carrying the cam plate 64. As the carriage comes to the end of its stroke at the left, the stop arm 43 therefore pushes the yarn slide 38 to the right, simultaneously causing movement of the yarn slide 39 to the left by means of the racks 41 and pinion 42. The movement of the slide 38 to the right causes the cam plate 64 to push down the roller 65, turning the trip lever 63 from the position shown in Fig. 3 to the position shown in Fig. 4. This opens the air valve 62 and the air begins to come out of the nozzles 57, 59. As the carriage moves to the right, the nozzle 59 in the back bed blows away the lint from in front of the needles, jacks and knitting cams in that bed. When the drive arm 12 reverses the direction of movement of the carriage, the nozzle 57 in the front bed clears away the lint in front of the instrumentalities knitting in the front bed. At the end of this return stroke the parts assume the position shown in Fig. 2 because the yarn carrier stop arm 43 has in the meantime moved into a position where it is in line with the left end of the back slide 39. This pushes the back slide 39 into operating position, and the rack teeth 41 and pinion 42 act once more, withdrawing yarn slide 38 to the left. This disengages the cam plate 64 from trip lever 63 and the trip lever, under pressure of the air in the valve 62, resumes its position shown in Fig. 3. This shuts off the air supply and the air-cleaning operation ceases. It will be observed that all this takes place automatically at regular intervals according to whatever arrangement of yarns has been chosen by the operator. It will be obvious that a yarn slide could be used which was not needed for a knitting yarn if it was desired to have the cycle of air cleaning different from all the yarn change cycles.

Assuming that a jack has gotten out of position and is struck by the carriage, such pressure will be exerted on the pressure release mechanism 17 as to cause the upper free end 18 of the drive arm 12 to be driven out of its connection with the release mechanism, thereby disengaging the carriage. This disengagement, as above mentioned, will cause the connection 17 to move down into contact with the rod 19, and that being in the electrical power circuit, the power will be shut off 60 and the machine stopped. Simultaneously with the breaking of the connection between the free upper end 18 of the drive arm 12 and the connection 17 on the carriage, the short pipe 49, as far as concerns movement longitudinally of the machine, will be swept out of the valve socket 48 as that socket moves ahead with the drive arm 12. The valve in the socket 48 will shut off the air supply and the parts will then be in the position shown in Figs. 5 and 6.

In Figs. 9, 10 and 11 I have shown a preferred modification of the embodiment of Figs. 1-8. In the modification the flexible hose which connects the stationary air supply to the carriage is coupled to the carriage only when the lint is being blown away. In addition, the mechanism on the

carriage for opening and shutting the air supply has been eliminated. I have also found that the lint tends to collect in the slots underneath the jacks as well as the needles. Therefore in my preferred embodiment nozzles are provided to remove the lint from in back of the slots occupied by the jacks when the latter are in their forward position. These two additional nozzles for cleaning the jacks are the nozzle 67 in the forward bed 1 and the nozzle 69 in the rear bed 2, both shown in Fig. 11, which are adapted to operate underneath the main knitting cams 30 when the jacks are still in their forward position after knitting. These nozzles are formed by holes through the knitting cams and are located at such a distance from the throat 3 between the two beds that when the needles are in their forward position with their butts riding along on the level 66 (see Fig. 7) their air blast is directed into the slots 5 in back of the jacks. By thus blowing the lint while the jacks and needles are in their forward positions, the slots and space under the cams can be completely cleaned out without any complications. The air supply means of my preferred modification of Figs. 9, 10, and 11 is controlled by an electric switch 70 actuated by a wire 71 connected to the yarn carrier slide stop arm 43 (see Figs. 2, 9, and 10). This electric switch 70 controls a roll of hose 72 and the furnishing of compressed air to that roll of hose by means of a solenoid air valve 73 attached to the stationary air supply 14. The solenoid air valve is connected to one end of the hose by piping 75. For the purpose of connecting the hose to the nozzles on the carriage there is a receiving valve 76 on the end of the hose and a complementary male tip 77 on pipe 78 carried by the carriage. This pipe is connected to distribution pipes 79 leading to nozzles 51 and 59 which are shown in the embodiment of Figs. 1-8. In addition, with the assistance of a short pipe 80 connecting the piping 79 to the rear or jack nozzle 67 in the front bed 2, the piping 79 connects the rear or jack nozzle to the rear bed 1 of the air supply. This can be seen in Fig. 11. These nozzles 67, 69 actually terminate as holes through the main knitting cams 30 at locations which, considering the direction of knitting of the two beds, will be seen to be opposite the latter part of the travel of the needles in their forward position during the knitting operation. In Fig. 11 the purl stitch cams 21 have been shown inserted, but it will be obvious that the cleaning operation can be carried out regardless of the position of those purl stitch cams.

Turning now to the connections between the hose and the piping 78, the complementary valve and tip 76, 77, of course, have the usual valve arrangement whereby when the two are pressed together the air can flow through from the hose to the piping 78.

I will now describe the parts which under the control of the electric switch 70 cause the rubber hose to be connected to the carriage only when it is desired to blow the lint and to automatically disconnect the rubber hose at the end of one or more reciprocations of the carriage. The hose is carried on a reel 81 which contains a spring (not shown) tending to keep the hose rolled up on the reel. In its fully retracted position shown in Fig. 9, the complementary air fittings 76, 77 can engage each other, but there is nothing to keep them in engagement during the normal operation of the machine. Since the solenoid air valve 73 keeps the compressed air shut

off from the hose during normal operation of the machine when not blowing lint, this contact between the fittings 76, 77 does no harm. When it is desired to connect the two fittings, the plunger 82 mounted in a cylinder 83 in a direction parallel to the fittings comes into action. The cylinder 83 is connected to the piping 75 between the solenoid air valve 73 and the hose reel 81. Therefore when the actuating wire 71 turns on the electric switch 70 and the solenoid valve 73 opens the air supply, the plunger is projected in the direction of movement of the beds. It engages against a plate 84 which carries the receiving fitting 76 and the end of the hose. The plate, resting on the carriage support 88, slides toward the pipe fitting 77 on the carriage and contact is maintained between the elements 76, 77 for some little distance until the plunger is at its extreme outermost position. Also mounted on the plate 84 is a latch 85 complementally shaped to a latch 86 mounted on the pressure release means 17 for the carriage. I have shown the latch 86 fixedly mounted on the pressure release means 17, and it will be obvious that since the pressure release means through the drive arm 91 travels with the carriage, if the two latches are engaged then the contact between the elements 76 and 77 for the air supply will be maintained. The latch 85 on the plate 84 is pivotally mounted and pressed into engaging position with the latch 86 by a spring 87. Normally the latch 85 is held up out of contact with the latch 86 by means of a bevel cam 89 fixed on the stationary cylinder 83 by virtue of a roller 90 on the latch 85. The bevel cam 89, whose real function is to unlatch the parts 85, 86 at the end of a reciprocation, is of such length that the roller 90 rides off the end of the cam before the plunger 82 comes to its extreme outermost position and therefore the spring 87 presses the latch 86 into engagement with the latch 85 before the two separate and the hose is carried out with the movement of the carriage to the other end of the machine and back with the spring in the reel 81 rolling up the hose as the carriage returns. Upon return of the carriage the roller 90 riding up on the bevel cam 89 disengages the latches 85, 86 by lifting the latch 85, the air supply being shut off and the plunger therefore yielding to the spring in the hose reel.

It will be observed, therefore, that whereas in Fig. 9 due to the fact that the yarn carrier slide stop arm 43 is in its forward position away from the hose 72 with the electric switch 70 open, the roller 90 is on the bevel cam 89 and the carriage reciprocates without the hose and the nozzles being connected up. In Fig. 10, where the stop arm 43 is moved to its rearmost position, the plunger 82 has pushed the hose out, maintaining contact between the elements 76 and 77 until after the roller 90 has ridden off the cam 89, and therefore, the drive arm 91, which is propelling the carriage, will continue to carry the hose 72 with it as it reciprocates.

The timing of the blowing of the lint in this modification is similar to that in the embodiment of Figs. 1-8. When the separating thread comes into use the pattern controls on the machine swing the stop arm 43 toward the rear bed, actuating the electric switch 70 and the solenoid air valve 73 with actuation of the other elements as above described. The blowing of the lint therefore can occur throughout a complete reciprocation. It is then cut off because the stop arm 43 is moved away from the closed position

11

of the electric switch before completion of the reciprocation. If desired, of course, the blowing can be stopped at any time before the reciprocation is completed, merely by moving the stop arm 43. The only limitation on the time of moving the stop arm is to coordinate it with the desired changes in the yarn. Obviously the blowing can be maintained for a single stroke of the carriage across the machine or for a complete reciprocation or any other portion of the stroke desired.

It might be noted further that my invention provides mechanism for cleaning the beds of any flat knitting machine and especially the difficult problem of cleaning a purl knitting machine in such way as not to upset the jacks, needles, and yarns in their operation, and that this is done automatically at controlled intervals. The efficiency of such machines is very much increased by providing this cleaning mechanism because, lacking it, it is necessary to take the machine out of operation for a considerable period of time at frequent intervals in order to clean it.

I claim:

1. A flat knitting machine in which there are independent needles, one or more beds containing the needles, a cam carriage and means adapted to move the carriage back and forth lengthwise of the bed, in combination with means providing a compressed air supply on the carriage and one or more nozzles connected to the air supply means and associated with the knitting cams on the carriage to blow lint away.

2. In a flat knitting machine according to claim 1, the combination of yarn change means and a valve for the air supply controlled by the yarn change means adapted to cause intermittent operation of the nozzle.

3. In a flat knitting machine according to claim 1, the incorporation in the air supply means of flexible hose and a stationary air supply connected to the flexible hose whereby the hose adjusts the stationary air supply connection to the movements of the cam carriage.

4. A flat knitting machine according to claim 1 in which the air supply means has a stationary source of air supply and connecting means adapted to connect the supply source to the reciprocating carriage only when it is desired to blow away lint.

5. A flat knitting machine according to claim 4 in which there is yarn change means controlling the connecting means.

6. A flat knitting machine according to claim 4 in which there are a hose reel, hose on the reel and complementary couplings on the hose and carriage to connect up the air supply.

7. A flat knitting machine according to claim 6 in which there are complementary latches associated with the hose coupling and carriage, in combination with a plunger controlled by the yarn change means to position the hose latch for engagement with the carriage latch.

8. A flat knitting machine according to claim 7, in combination with a stationary latch release adapted to engage one of the latches, whereby the hose is disconnected at the end of a reciprocation of the carriage.

9. A flat knitting machine according to claim 8, in combination with a cylinder containing the plunger and connected to the air supply, and an air valve between the air supply and the cylinder controlled by the yarn change means, whereby the turning on of the air in the hose actuates

12

the plunger, causing latching of the hose to the carriage and blowing away of the lint.

10. A purl knitting machine according to claim 1 in which there are both independent needles and jacks in the needle bed or beds and there are one or more nozzles located ahead of the knitting cams and one or more nozzles located so as to blow below the jacks.

11. A purl knitting machine according to claim 10 in which the nozzle or nozzles for blowing lint away from the jacks are positioned at a point where the jacks are advanced and the nozzles blow in back of them.

12. A purl knitting machine according to claim 11 in which the nozzle or nozzles for blowing lint away from the jacks are so positioned as to also blow lint from between the bed and the cams.

13. In a flat knitting machine according to claim 1, the positioning of a nozzle so that it is tipped away from the knitting cams and the active yarn carrier.

14. In a flat knitting machine according to claim 1, the positioning of the nozzles so that they blow lint away from the knitting cams on both directions of movement of the carriage.

15. A flat knitting machine according to claim 1 in which one or more of the nozzles connected to the air supply means are ahead of the knitting cams on the carriage.

16. A flat knitting machine according to claim 15 in which there are two compressed air nozzles each located on the carriage ahead of the knitting cams in a different direction, whereby lint is blown away from the cams on movements of the carriage in both directions.

17. A flat knitting machine according to claim 15 in which there are two needle beds, in combination with two compressed air nozzles on the carriage, one over each bed, ahead of the knitting cams, adapted to blow lint away on movements of the carriage in both directions.

18. In a flat knitting machine according to claim 1, the provision of a valve on the carriage in the air supply means and a trip lever adapted to release the air intermittently.

19. In a flat knitting machine according to claim 18, a plurality of yarn change slides mounted on the carriage and stop arm means for operating the slides, in combination with a cam plate on one of the slides, a trip lever operable by the cam plate and a valve operated by the trip lever to release the air intermittently.

20. In a flat knitting machine according to claim 19, the arrangement of the parts so that the valve is open when the slide carrying the cam plate is in yarn-feeding position.

21. In a flat knitting machine according to claim 20, two yarn carriers, two yarn slides adapted to control the putting of the yarn carriers into operation and their removal, said two yarn slides being so associated that the putting of one into action causes the removal of the other, and yarn carrier stop arm means at one end of the machine adapted to push the slides into action selectively, in combination with a valve on the air supply means mounted on the carriage, a trip lever for the valve pivoted on the carriage and cam means on one of the slides to operate the trip lever, whereby the selection of the yarns gives automatic operation of the air cleaner for one or more complete reciprocations of the carriage at controlled intervals.

22. In a flat knitting machine according to claim 1, an arm to drive the cam carriage in re-

13

ciprocator movement and means adapted to release the carriage from the arm if the latter meets an obstruction, in combination with a pipe and socket valve connection for the air line associated with the drive arm and carriage and adapted to automatically break the air line connection when the arm and carriage are disconnected.

23. In a flat knitting machine according to claim 1, the provision with the pipe and socket valve connection of a spring-pressed pivotal mounting for the pipe whereby the pipe is normally spring-pressed in the socket but rocks out of the socket when the drive arm and carriage are disconnecting.

24. A purl knitting machine in which there are double-ended needles and two flat needle beds, a cam carriage adapted to move back and forth lengthwise of the beds for knitting, in combination with a supply means providing compressed

14

air on the carriage and one or more nozzles on the carriage attached to the air supply means adapted to blow lint away.

25. In a purl knitting machine according to claim 24, the positioning of one or more of the nozzles opposite a point where the needles and jacks are held against longitudinal movement by cams and the needles are not lying across the throat between the beds.

26. In a purl knitting machine according to claim 24, the combination of a purl cam block on the carriage adjacent the knitting cam block for each bed, the nozzle being so located that there is a cam in the purl cam block adjacent the nozzle adapted to hold needles from tipping up just after passing the nozzles.
